UNITED STATES PATENT OFFICE

2,440,894

NEUROPATHIC AID

Orville S. Caesar, Barrington, Ill.

Application April 19, 1946, Serial No. 663,474

3 Claims. (Cl. 128—80)

1

This invention relates to improvements in devices adapted to assist a patient to walk, following neurologic or muscular dysfunction, due to disease, or trauma.

While the invention is believed to be useful in more than one neurologic or orthopedic condition, the device herein was particularly designed for use in a condition known as "drop-foot," in which there is the inability to voluntarily move the foot upwardly. The condition results from palsy of the anterior tibial nerve. Such a patient needs a device adapted to apply just the right degree of upward pressure on the foot to compensate for the loss of nervous control of muscular power, and to permit and to assist to such ankle-joint motion as is needed in walking. Since there are varying degrees of palsy and since varying degrees of pressure support are sometimes needed during the course of healing of a particular case, it is needful to provide some simple easily applied device that will subserve such requirements. The patient also needs a device which he can himself take off and put on, and by which just the right degree of upward force needed in his individual case can be applied. This invention provides a device highly adapted to the above needs.

Moreover the device should be comfortable; should be easily attachable and removable; should be light in weight as possible; should be strong and durable; should not be unsightly; should have a minimum of projecting parts; and should be relatively cheap. The present invention provides all of the above mentioned qualities and advantages.

I am aware that various devices of this general nature have been heretofore made but all of them have some objections, which I have overcome by the structure shown herein. For example, some of the prior devices must be built into the shoe at the time of manufacture so that new shoes must also be purchased to obtain the device. No change or adjustment can be made. Others are provided with pivoted joints which cause friction and which are unsightly. Others have leg-engaging portions that engage the medial rather than the posterior surface of the leg. Others use straps which encircle the leg and unduly constrict and cause considerable disagreeable friction. Others are attached to points laterally of the shoe or heel and form a rigid support. Others have parts which engage, rub the ankle joints and which are often unbearably painful.

Other objections in regard to various prior

2

devices known to me are: Difficulty in obtaining the right "feel" and the right degree of orthopedic pressure; inability to adjust the device in any way whatever to make it comfortable, for all motions of the foot and leg in walking; difficulty of attachment; unsightliness of the devices by which attachment is made; projection of parts in such manner as to be caught in the bottom of the trousers; and projection of the parts in such manner as to make the wearer stumble and/or fall due to engagement of the parts by the shoe of the opposite leg.

The nerves supplying the anterior muscles of the leg are often injured during the course of poliomyelitis, and aids of the kind herein are therefore frequently worn by children. They may be worn for extended periods of time. It is then important; that the device be of a minimum weight; that the parts project laterally only in a minimum degree, and not in a manner to trip the wearer; that the device be capable of easy attachment and detachment and; that provision be made for varying degrees of upward pressure. This invention provides for all of the above needs.

Features and advantages of the invention will appear in the description of the drawings, and in said drawings—

Fig. 1 is a side elevation showing the device applied and with the leg-engaging element partly in section;

Fig. 2 is a rear view of Fig. 1;

Fig. 3 is a vertical transverse section on line 3—3 of Fig. 1 showing the way in which the device is attached;

Fig. 4 is a bottom plan view;

Fig. 5 is a vertical longitudinal section taken on line 5—5 of Fig. 4; and

Fig. 6 is a plan section taken on line 6—6 of Fig. 1.

Now referring to the drawings. The shoe has the usual upper 1, heel 2, bottom instep surface 3, forward vertical heel surface 4, forward sole portion 5, and insole 6.

It is important to provide a very simple form of attaching means. To this end a single opening 8 is made through the instep portion of the sole about midway of its transverse dimension. Into this opening 8 is inserted an interiorally threaded cylindrical stud 9. A press-fit connection is made. The stud is of one piece with a thin circular plate or head 10 and this head is preferably embedded in the bottom surface of the inside of the shoe with its upper face flush with that inner surface. The head has punched-out

projections 11 which enter the leather to prevent rotation of the stud, and the head may have openings for suitable fastening devices. The insole 6 covers the head 10.

The shoe is now conditioned for the attachment of my pressure-applying structure which may be considered as a lever-like structure comprising a pair of arms having a common fulcrum, the lever being made of material which will apply yielding pressure. The fulcruming structure comprises a metal block 12 having a central opening 13 for the reception of a fastening screw 14. This screw passes through the opening 13 of the block and has threads engaged with the interior threads of the stud 9. The block has a 15 countersunk depression 15 to receive the conical head 16 of the screw, and the head has a screw driver slot 17 of a width to receive a coin such as a dime, to be used as a screw driver. Thus, a single screw secures the block to the shoe.

The rear face of the block engages the front face 4 of the heel and the upper face of the block is forced tightly against the under surface of the instep by means of the screw. Engagement of the block with the heel prevents block rotation. If the front surface 4 of the heel is originally curved transversely of the shoe as is frequently the case, the surface is preferably made flat throughout its length crosswise of the shoe.

The force-applying element is herein made of a single piece of wire, such as piano wire. The wire is relatively small in diameter so as to be as inconspicuous as possible. The quality of the wire is important. The wire must be resilient, that is, capable of spring force-applying action. Various grades of wire resiliency can be had to obtain the correct pressure characteristic for each case. This wire material is formable, that is, can be given a suitable form as shown. The elements of the long arm can be manipulated or bent by the user to slightly change its contour conformable to the needs of optimum comfort, while the force-applying characteristic is at all times maintained.

In forming the arms the wire is first bent midway of its length to provide the forwardly extending short arm 20 of the lever system, two coil spring sections 21, 22 are then formed so as to be axially aligned and lie at opposite sides of the vertical faces of the block 12. Pins 25 are threaded into the block and pass through the coils and each pin has a screw driver slot 26. These pins anchor the lever structure and act as supports for the coils 21, 22 and act as fulcrums for the lever arms.

From the outer end of each coil the wire is extended horizontally as at 27 in a direction substantially parallel with the axis of the coils to a point beyond vertical planes passing through the side surface of the heel portion of the shoe. The wire is then so bent as to slant upwardly and rearwardly as at 28 in opposition to the sides of the rear portion of the upper. The wires curve as at 29 and extend upwardly as at 30 in a more upright position and are preferably slightly curved in a forward direction and have their upper ends attached as at 31 to the outer side of a thin plate 33 of light steel of somewhat U-shaped form as viewed from the top. The connection of the plate 33 is preferably made by welding. The plate is suitably padded as at 34 and the padding is covered with a suitable finishing material 35, preferably leather.

It is through this padded element that pressure is transmitted to the posterior portion of the leg. 75

The padded leg element is not secured to the leg, but is so placed that relative movement between the element and the leg can occur to avoid discomfiture. Padding prevents any painful action due to rubbing and there is no constricting action of any band about the leg to interfere with the circulation.

As before stated, an important advantage of this invention is the use of wire material of special spring steel quality and of relatively small diameter for applying the pressure. This wire has two qualities, both of which are important. The first is that the wire has the proper resiliency to obtain the proper degree of pressure, respectively upwardly against the instep and forwardly against the back of the leg. The second is that elements of the long arm which includes the portions 29 and 30 are to some extent formable by hand manipulation to make this arm conform to the leg contour and pressure needs of the particular person who is wearing the device. In no device known to me, except the device herein, can slight but needful variations in degrees of pressure be so easily obtained.

Fig. 1 at 40 shows in dot-and-dash lines how the contour of the portions 29 and 30 of the leg pressure arm can be changed. In Fig. 2 dot-and-dash lines indicate at 41 how the elements 30 can be bent inwardly, and it is understood that they can also be bent outwardly. Change of contour of the wire elements may be utilized to slightly change the point of application of the pressure. For example, referring to Fig. 1, if the portion 30 is bent outwardly the padded leg-engaging element will be moved slightly downwardly. If 30 is bent to a straighter position the leg-engaging element will be moved slightly upwardly. Moreover, by such a manipulation pressure point relationship between lever 20 and the leg lever, both in relation to the ankle joint, are obtainable. This feature is related to the pressure "feel" of the patient. Generally speaking, each patient needs a special adjustment of the device to suit him.

If the user wishes to remove the device while sitting, this can be easily and quickly accomplished by unscrewing a single screw.

To attach the device, all that is necessary is to stand on the device by placing the sole on the arm 20 to flatten it. Then the opening in the block is registered with opening in the shoe, and then the screw 14 is applied and screwed into place using, if desired, the edge of a coin to act as a screw driver.

It will be noted that the attaching point for the arms is disposed below and forwardly of the ankle bones or ankle joint, and that the portions 28, 29 lie at a level below the ankle bones. The rear arm is so shaped that its parts never assume a position in opposition to those bones and therefore can never rub or injure them.

It is to be noted that the single-piece resilient leg-engaging and instep-engaging element has two parts, one of which applies an upward thrust against the instep and the other of which applies a forward thrust against the posterior surface of the leg. Both thrusts having a common fulcrum point which lies on a traverse line, disposed forwardly of and below the ankle joint. Thus, the forward part 20 tends to raise the foot and thus oppose foot-drop tendency and this action is performed by what may be considered one arm of a lever, the upper part of the other arm of which engages the posterior of the leg.

It will be understood that the degree of resilient

action or thrust action of the arms can be varied, and it is contemplated herein to provide individual resilient elements of different degrees of resiliency, any one of which may be selected for substitution, so that the patient has a choice which permits him to obtain a device having exactly the right resiliency or "feel" suitable for his particular case.

It is to be noted that the parts 27 which project laterally beyond the shoe, so project at such a low level and forward position as to preclude the possibility of the trousers catching thereon. Above this point the wire arms are so formed as to preclude the possibility of the trousers being caught therein. Moreover, there is a minimum of projection, which makes it unlikely that the foot of the opposite leg will accidentally engage any projecting part. Therefore, the manner of attaching the device entirely to the underside of the shoe and forming all laterally projecting parts in a manner to prevent snagging of the trousers, or tripping, is an important feature.

During walking the leg of the foot which is moving forward, swings rearwardly about the ankle joint as a center. When this occurs greater rearward pressure is put on the leg-pressing arm to move it rearwardly and therefore greater upward pressure is brought to bear against the bottom of the instep to keep the foot raised. When the leg swings forwardly about the ankle as a center, the leg-pressing element moves forwardly but its tension is lessened and correspondingly the tension on the element 20 is lessened. Thus, varying pressures occur conformably to the position of the leg and foot in walking.

An important advantage is that the present device can be removed and applied to any one of several shoes and that substitute supporting or force-applying elements can be used, each painted to have the same color as the shoe on which the device is to be worn. Where the color of the wire and of the shoes and the hosiery are the same, the brace is barely noticeable. This is important to all who must wear corrective, or supportive appliances.

What I claim is:

1. A device of the class described comprising, a block having an opening through which a fastening device is adapted to be passed to secure the block to the undersurface of the instep of a shoe, said block having at each opposite side a lateral projection adapted to lie horizontally when the block is attached, said projections being axially aligned and adapted to be disposed transversely of the shoe, a structure made of a spring wire having spring coils, one supported on each lateral projection, the inner end of the coils merging to form an arm adapted to apply upward pres-

sure against the under surface of the shoe forwardly of the block and the outer ends of the coils merging into extensions which pass laterally then rearwardly and upwardly at the outside of the shoe to a point rearwardly of the leg and above the ankle of the wearer of the shoe, the upper ends of said extensions being attached to a padded element which is adapted to engage and to be pressed against the posterior surface of the leg by said extensions.

10 2. A device of the class described comprising, a shoe having an opening extending entirely through the instep portion of the sole, an interiorly threaded stud secured in said opening, a block engaging the undersurface of the instep and the forward surface of the heel, a screw passing through the block and threaded into said stud and securing the block, said block having extending from each opposite side a pin having threaded engagement with the block, a resilient wire structure having spring coils one surrounded and supported by each pin, the coils at their inner end merging into a spring arm which applies upward pressure against the instep at a point forwardly of the block, the outer end of each coil merging into an arm which extends laterally beyond the sides of the shoe, then rearwardly then upwardly, said arms being attached to an element which is adapted to be pressed into engagement with the posterior surface of the leg of the wearer of the shoe.

20 3. A device of the class described comprising a spring wire structure provided with axially aligned coils adapted to underlie the instep of a shoe, the adjacent ends of said coils providing an arm extending forwardly of the shoe and pressed upwardly against the bottom thereof by the spring force of said coils, the opposite ends of said coils providing arms extending upwardly laterally of the shoe and being pressed forwardly by the spring force of said coils, and means for securing said coils in position under the instep of a shoe and within the marginal edges thereof.
